HANDLE ATTACHING DEVICE

Robert Cricco, Hoboken, N. J.

Application September 9, 1937, Serial No. 163,023

4 Claims. (Cl. 306—40)

My invention refers to framed devices having handles and refers particularly to devices of the character described having transparent handles and particularly transparent glass handles.

5 In many articles such as mirrors, hair brushes, and other toilet articles it is desirable that they have glass handles particularly for purposes of attractiveness and artisticness, but the means adapted for this purpose have been expensive, 10 cumbersome and commercially ineffective.

It is evident that in articles of the described character none of the attachment means should extend into the handle, as such extensions would require a hollow handle which is considerably 15 more expensive and more fragile than a solid glass handle and the thus extended attaching means would show through the glass handle thus materially decreasing its attractiveness.

In articles of the character described, and especially in mirrors, it has been found necessary to place a supporting, or strengthening, element between the mirror and the back member, the objects of this element being to make the assemblage more rigid and to act as an anchorage 20 for the elements of the handle and its attachment to the device.

Prior attempts have been made to accomplish this result by attaching the handle directly to an extended portion of this supporting element, 25 but these devices have proved ineffective and of little commercial adaption as the entire weight of the device is thus thrown upon the means connecting the supporting element to the glass handle and as these elements must necessarily 30 be small, distortions and breakage of these parts result from use.

Among the objects of my invention is a distribution of the weight of the article between the connecting elements of the supporting member 40 and the frame of the article, thus removing a large portion of the strain from the connecting means, which has proved objectionable, and transferring it to a connection between the handle and the frame of the device.

45 To accomplish my results I employ the supporting plate as a means for closing the frame and enclosing therein the necessary elements such as a mirror and back, or the back of a brush. I thus have a completed article with the exception of a handle.

Instead of employing the usual method of attaching the handle directly to the supporting plate, thus placing all of the strain upon this attachment; I attach the supporting plate to a 50 ferrule of such size and shape that it encompasses a portion of the frame and abuts thereon, thus throwing a portion of the weight and strain of the article upon the ferrule; and I then attach a handle to the ferrule.

60 It will thus be seen that when the device is held

by the handle the entire strain incident to the weight of the article is not upon a connection between the handle and the supporting plate, but is distributed between the supporting plate, a ferrule, the frame of the article and the handle. 5

It is evident, therefore, that a device of my construction is much stronger than previous devices of the construction described.

A further advantage of my device is that it 10 allows of the use of a solid transparent handle, thus overcoming the objectionable features incident to the use of a hollow handle within which the connecting elements are discernable.

The aforementioned, and other new and valuable features of my device will be evident upon 15 a consideration of my specification and its accompanying drawing which are directed particularly to a mirror, although I wish it to be understood that my invention is not limited in its application to this particular toilet article. 20

The accompanying drawing, in which similar parts are designated by similar numerals, illustrate modifications of the devices of my invention.

Figure 1 is a front view of one form of my 25 device applied to a mirror.

Figure 2 is an enlarged broken section along the line 2—2 of Figure 1.

Figure 3 is an enlarged section through the 30 line 3—3 of Figure 2.

Figure 4 is an enlarged fragmentary view of the mirror and frame of the device of Figure 1.

Figure 5 is an enlarged perspective view of the 35 supporting element of the device of Figure 1.

Figure 6 is an enlarged bottom view of the connecting means of the device of Figure 1.

Figure 7 is an enlarged top view of the connecting means of the device of Figure 1.

Figure 8 is a section through the line 8—8 of Figure 7 showing the washer element of the 40 device.

Figure 9 is a modified form of the supporting member.

Figure 10 is an additional modified form of the 45 supporting member.

The particular form of the device of my invention shown in Figures 1 to 8 comprises a channel shaped rim or frame 11, having the two outwardly flared end members 12—12, each said end member 12 having a recess 13 therein. Within 50 this frame 11, and to be fixedly held therein when the device is assembled, is a mirror 14, cardboard fillers 15 and 16, a metal supporting device 17, cardboard fillers 18—18, a metallic sheet 19 and a decorative outer back 20. 55

The fillers are employed to protect the mirror 14 and the outer back 20, while the metal supporting device serves as a support for the device and as a means for maintaining the frame 11 in closed position, as will be explained later. 60

The metal supporting device 17 has a flat base 21 and an extended flat flange plate 22, the plane of which is at right angles to the plane of the supporting flat base 21. The flange plate 22 has two arms 23-23 and an internally threaded hole 24 through its central portion, so positioned that the extended portion of a bolt threaded therethrough will be within a depressed channel 25 in the base 21.

10 In order to assemble the frame 11 and its contained elements, the several parts are assembled as shown in Figure 2, with the arms 23-23 of the supporting member 17 positioned within the recesses 13-13 of the frame extensions 12-12 and turned down as shown in Figure 3. In order that a firm assemblage of these elements may be obtained, the two extended members 12-12 are pressed together before the arms 23-23 are turned down and the mirror 14, the back 20 and 20 the intermediate elements are thus firmly enclosed within the frame 11.

15 The handle-carrying element of the device is in the form of a ferrule and is adapted to have the three-fold usefulness of covering the elements employed for closing the frame, of firm attachment to the frame and as a means for firmly holding a solid transparent or other handle.

20 The ferrule may be annular, elliptical or of 30 any other desired adaptable form and may be plain or ornamental in design.

25 The ferrule comprises a side 26 forming the handle-receiving compartment, or recess 27, thence extending inwardly forming the shoulder 28, then outwardly and upwardly into a frame-receiving member 29.

30 This frame-receiving member 29 is of such shape and size as to abut firmly upon and against a portion of the frame as is shown in Figures 1 and 2.

40 The ferrule is attached to the frame 11 as follows: a washer 30 having a central opening 31 and an extended flange 32 is placed within the ferrule, the flange 32 abutting upon the ferrule shoulder 28, and a threaded bolt 33 is passed through the hole 31 of the washer 30 and threaded tightly into the threaded hole 24 of the flange 22 of the supporting member 17.

45 It will thus be seen that the ferrule entirely encloses all of the elements employed in attaching it to the frame, and that a compartment is formed within the ferrule for the reception of a handle 34, which is firmly attached therein by means of cement or by other suitable means.

50 The plate 21 is described in Figures 1 to 8 as being of elongated form, but it may have the same contour as the mirror as shown in Figure 9 adapted to a round mirror, it may be of ring formation as shown in Figure 10, which is also adapted for a round mirror, or it may be of other shapes if desired, the particular shape of this element not being a limitation of my invention.

55 The flange 22 may be an extension of the supporting member 17, or may be welded thereto or otherwise attached thereto.

60 The channel 25 of the supporting member 17, may be any desired length or may be entirely eliminated if desired, in the latter case it being advisable to off-set the threaded hole 24 from the center of the flange 22, or to otherwise arrange the elements to take care of that portion of the threaded bolt 33 which extends beyond the flange 22.

65 The fillers within the frame and between the

70 mirror and the back may be changed in number and arrangement or entirely eliminated as desired.

75 It will thus be noted that my invention presents means for producing framed articles in which a solid transparent handle of glass or other material can be incorporated without disclosure of the means adapted for closing the frame or for the attachment of the handle.

80 I do not limit myself to the particular size, shape, arrangement, number or material of parts specifically shown and described, as these are given solely for the purpose of clearly describing my invention.

85 What I claim is:

1. A device adapted to connect a handle to an article comprising an article; a split frame carried by said article, the open ends of which are extended outwardly, each extended end having an opening therethrough; a supporting member carried by said article, an extended flange carried by said supporting member having a threaded opening therein, the ends of said flange being adapted to pass through the openings in said frame ends; a ferrule adapted to encompass said frame ends and abut upon said frame, and means adapted to fixedly combine said frame ends to said flange and to cause said ferrule to forcibly abut upon said frame. 15

2. A device adapted to connect a handle to an article comprising an article; a split frame carried by said article, the open ends of which are extended outwardly, each extended end having an opening therethrough; a supporting member carried by said article, an extended flange carried by said supporting member having a threaded opening therein, the ends of said flange being adapted to pass through the openings in said frame ends; a ferrule adapted to encompass said frame ends and abut upon said frame, and means adapted to bring said frame in abutment with said article and to maintain them in such abutment, to fixedly combine said frame ends to said flange and to cause said ferrule to forcibly abut upon said frame. 30

3. An article of manufacture comprising an article; a split frame carried by said article, the free ends of which are extended outwardly; a supporting member carried by said article, a portion of said supporting member extending outwardly from said frame and between said frame ends and having a threaded opening therein; means carried by said supporting member maintaining said frame in holding abutment upon said article; a ferrule enclosing said frame ends; threaded means attaching said ferrule to said supporting member and in forced abutment upon said frame and a handle carried by said ferrule. 45

4. An article of manufacture comprising an article; a split frame carried by said article, the free ends of which extend outwardly, each free end having an opening therein; a supporting member carried by said article within said frame, a portion of said supporting member extending outwardly from said frame and between said frame ends; two arms carried by said supporting member passing through the openings of said frame ends and maintaining said frame ends in fixed position with respect to each other; a ferrule enclosing said frame ends, a flange within said ferrule; means attaching said flange to said supporting member and in forced abutment upon said frame and a handle carried by said ferrule. 60

65 ROBERT CRICCO.
